United States Patent Office.

GEORGE W. GOODWYN, OF PETERSBURG, VIRGINIA.

Letters Patent No. 78,081, dated May 19, 1868.

IMPROVEMENT IN CHURN.

The Schedule referred to in these Letters Patent and making part of the same.

TO ALL WHOM IT MAY CONCERN:

Be it known that I, GEORGE W. GOODWYN, of Petersburg, in the county of Dinwiddie, and State of Virginia, have invented a new and improved Churn; and I do hereby declare that the following is a full, clear, and exact description of the construction and operation of the same, reference being had to the annexed drawing, making a part of this specification, in which my invention is represented by a perspective view.

This invention relates to an improved means for operating the churn, whereby the work of churning can be performed much more easily than by any of the old methods.

In the drawing, A represents an old-fashioned upright churn, having a vertically-reciprocating dasher, B, and resting upon a slotted plank, C. D is an upright post, supported upon the plank C, and provided with shelves or flanges, d d', which operate as guides for the handle of the dasher. E is a spiral spring, attached to the under side of the upper flange, d', and coiled around the handle of the dasher, operating to force the latter down in the churn. The dasher is raised by the operation of a treadle, F, connecting-rod or strap G, lever H, attached to a rocking-wheel, I, or simply pivoted on a fulcrum in the upper end of the post D, and strap or rod J, connecting the short arm of the lever, or the perimeter of the wheel, with the top of the churn-dasher. The only object in using a wheel in preference to a lever is, to give a perfectly even vertical motion to the dasher, without swaying it in one direction or the other.

The whole apparatus is simple and cheap, and by using it a person will be enabled to sit in his chair, employing his hands about other work, while, with one foot, he performs the operation of churning, thereby saving all the time required for the latter operation, besides performing it with greater ease than in the old way.

I am aware that treadles have been used in connection with a revolving shaft or wheel, for the purpose of working a churn-dasher, the treadle operating to give the wheel or shaft a continuous rotating motion. I do not claim anything of that nature as my invention; but

What I do claim, and desire to secure by Letters Patent, is as follows, viz:

The combination of a rocking-wheel or lever, I, with the straps G J, treadle F, dasher D, and spring E, the whole constructed and operating in the manner and for the purpose described.

GEO. W. GOODWYN.
